US0D1065823S

(12) United States Design Patent (10) Patent No.: US D1,065,823 S
(45) Date of Patent: * Mar. 11, 2025

(54) HANDBAG

(71) Applicant: Bottega Veneta S.R.L., Montebello Vicentino (IT)

(72) Inventor: Matthieu Blazy, Milan (IT)

(73) Assignee: BOTTEGA VENETA S.R.L.

() Term: 15 Years

(21) Appl. No.: 29/848,802

(22) Filed: Aug. 5, 2022

(30) Foreign Application Priority Data

Feb. 25, 2022 (EM) 008871693-0010

(51) LOC (15) Cl. 03-01

(52) U.S. Cl.

USPC D3/242; D9/432

(58) Field of Classification Search
